THE COLUMBIA PLANOGRAPH CO., WASHINGTON, D.C.

UNITED STATES PATENT OFFICE.

EARL G. WATROUS, OF CHICAGO, ILLINOIS.

SHOWER-HEAD.

1,319,738.

Specification of Letters Patent. Patented Oct. 28, 1919.

Application filed June 1, 1915. Serial No. 31,357.

To all whom it may concern:

Be it known that I, EARL G. WATROUS, a citizen of the United States, residing at Chicago, in the county of Cook and State of Illinois, have invented certain new and useful Improvements in Shower-Heads, of which the following is a specification.

My invention relates to a shower head adapted for use in connection with a lavatory faucet, barber's shampoo cock or a bath cock and the like and the object thereof is to provide a simple and efficient shower head characterized more particularly by the provision of a normally closed throttle valve and a relief valve interposed between the supply connection and the throttle valve with result, first, that the relief valve provides a uniform pressure of water past the throttle valve and through the usual sprinkler head and, second, the water supply is permitted to escape through the relief valve in case the throttle valve is closed. Other novel and advantageous features of construction and operation will be apparent from the description hereinafter given.

In the drawing, Figure 1 is an elevation of my shower head attached to a bath cock representing one of the practical applications thereof; Fig. 2 a section of the throttle valve mechanism showing the sprinkler head in elevation; Fig. 3 a section of the relief valve mechanism and associated parts and Fig. 4 a section on the line 4-4 in Fig. 3 but on a larger scale.

In the drawings I have shown one application of my shower head by showing it in connection with a bath cock indicated generally by the reference figure 1 but it will be understood that my invention is not to be limited to any particular application as the same may be used in connection with any source of water for the purpose of providing a regulated supply of water either hot or cold or mixed, such other applications being represented by lavatory faucets, barbers' shampoo cocks, etc.

My shower head comprises a conduit containing toward one end relief valve mechanism and toward the other end throttle valve mechanism. By preference and as shown this conduit includes an intermediate flexible portion or hose 2 attached at its ends to the casings 3 and 4 of the relief valve mechanism and throttle valve mechanism respectively. The casing 4 which is shaped to form a handle or grip may be provided with

a sprinkler head 5 of any suitable or desired construction, the same being here shown as a rose such as used in shower devices. The shower head is adapted to be connected with the source of water supply such as the bath cock in any suitable manner as by means of a coupling hose 6 fitting over the supply connection 3^a of the relief valve mechanism and over the nipple 7 of the bath cock. By preference the casing 3 is provided with a projecting tube 8 fitting into the nipple 7 and adapted to keep the casing in alignment with the nipple in case of any pull upon the shower device at an angle to the nipple.

Referring to the relief valve mechanism the interior thereof is provided with an outlet or relief port 9 which is governed by a relief valve of suitable construction such as the disk 10 normally held to its seat with a yielding predetermined pressure by means of the coiled spring 11 bearing at its ends respectively against the valve itself and against a screw plug 12 screwing into the outer portion of the casing, this plug being provided with a central opening 12^a through which the final relief discharge takes place. The screw plug 12 may be screwed all the way in and thereby provide a fixed load upon the valve or it may be screwed in only partially so that by screwing the same farther inwardly the load may be changed, that is increased by increasing the tension of the spring. The tension of the spring upon the valve is adjusted slightly in excess of that degree of pressure of water desired in the sprinkler head with the result that excess pressure of water will be relieved through the relief valve which will open against the pressure of the spring and the proper and uniform pressure of water will be supplied through the sprinkler head.

The casing 3 is provided with a lateral connection 13 to which one end of the hose 2 is coupled in suitable manner but preferably in the manner shown, that is by means of the bushing 14 having its inner flanged end screw-threaded into the connection 13 and provided with an annular reduced portion 14^a intermediate its length to receive the inner end of the hose. The connection 13 has its opening flared at 13 in order to cooperate with the reduced portion 14^a in receiving and eventually clamping the end of the hose when the parts are screwed together in the manner shown in Fig. 3.

Referring next to the throttle valve the casing 4 is provided with a discharge port or outlet 15 governed by a throttle valve 16 normally held to its seat by a yielding pressure. This valve is provided with a stem 17 which projects through a chamber 4^a within the casing and which is operatively connected at its upper end to a push button 18 mounted to slide in the upper end of the chamber 4^a. This button is mounted to slide in the casing in a direction longitudinal of the valve stem and against the tension of the coiled spring 19 arranged within said chamber 4^a. This chamber is provided with packing 20 to prevent escape of water past the valve stem and into the chamber 4^a.

The casing 4 is provided with an extension 4^b to which the outer end of the hose 2 is coupled or clamped in a manner similar to the clamping shown in Fig. 3, the means for this purpose consisting of a screw-threaded bushing 21 screwing into such extension and provided with the reduced portion 21^a intermediate its length to receive the inner end of the hose 2, the opening in the extension 4^b being flared at 4^c to operate with said reduced portion 21^a in the clamping of the hose. Also by preference the bushing 21 is provided with a tube 22 adapted to hold the hose in alinement with the casing 4 and prevent binding of the hose at a point adjacent its connection with such casing.

The sprinkler head 5 which is here shown in the form of the usual rose is by preference removably secured to the casing 4. As shown this casing is provided with a lateral extension 4^d to which the nipple portion 5^a of the rose or head is screwed.

By means of my shower head water either hot or cold or mixed may be supplied with a uniform pressure and any excess pressure is automatically taken care of by the relief valve mechanism and moreover by means of my invention the water supply can be controlled adjacent the sprinkler

head by a throttle valve under the ready control of the sprinkler, the casing of the throttle valve being fashioned to constitute a handle or grip for holding and manipulating this head. Furthermore, the throttle valve which is normally held to its seat with a yielding pressure may be permitted to close without the necessity of shutting off the supply of water from the bath cock, for instance, in which event the water will flow through the relief valve mechanism without any danger of forcing the shower head off from its connection with the bath cock at the hose connection 6 as might otherwise result.

I claim:

1. A bath shower adapted to be attached to a faucet, comprising a casing, means for connecting the casing to the faucet, a sprinkler head, a hose connecting the sprinkler head and casing, a manually operable valve in the sprinkler head, and a valve in the casing automatically operable to open to permit the faucet to discharge directly through the casing when the valve in the sprinkler head is closed. 65

2. A bath shower adapted to be attached to a faucet, comprising a casing, means for attaching the casing to the faucet, a sprinkler head, a hose connecting the sprinkler head to the casing, a normally closed valve in the sprinkler head, an automatically opening valve in the casing, means for yieldingly maintaining said valve closed, and means for adjusting the resistance of the last mentioned means whereby the water will issue from the head at a constant pressure when the valve in the sprinkler head is open and will permit the entire discharge from the faucet to escape directly from the casing when the valve in the sprinkler head is closed. 75 80 85

EARL G. WATROUS.
